EARTH TAMPER

Matthew S. Ross, Riverton, Wyo.

Application January 17, 1938, Serial No. 185,453

4 Claims. (Cl. 94—50)

This invention relates to improvements in earth tampers of the "sheep foot" type.

In making earth fills such as in road grading, dam construction and the like, it is essential that the earth be compacted and thoroughly tamped to prevent future settling. To effect thorough compacting of freshly filled earth, the "sheep foot" type of tamper has been extensively used but heretofore they have been tractor-drawn.

When a tractor is used to draw the tamper the surface of the fill is unavoidably compacted by the tractor which tends to prevent the "feet" or lugs of the tamper drums from penetrating into the earth. This produces an inferior result in that strata are left in the fill that are not thoroughly tamped. Further, when a tamper of this type is drawn by a tractor, the rolls or drums tend to skid or slide along over the earth instead of turning, which defeats thorough tamping.

Again, tractor-drawn equipment is difficult to turn around or to reverse.

It is an object of the present invention to provide a self-propelled earth tamper, of the "sheep foot" type, that can be steered and reversed, and which is provided with individual drives to each drum or roll so that the above enumerated difficulties are substantially eliminated, and the rotation of the drums is assured.

Other objects and advantages reside in details of design and construction, inclusive of a novel and efficient renewable lug or foot for the tamper rolls and novel provision for steering the machine. These features will be more fully disclosed in the following description and in the drawings wherein like parts have been similarly designated and in which:

Figure 1 is a general plan view of a tamper built according to the present invention;

Figure 2 is a side elevation of the same;

Figure 3 is a fragmentary end elevation as indicated by arrow 3 in Figure 2, and illustrating certain details of construction;

Figure 4 is an enlarged sectional detail view; and

Figure 5 is an elevation as indicated by arrow 5 in Figure 4.

In the drawings reference character 15 denotes a general supporting frame that is divided into two relatively movable sections 16 and 17, 50 that are pivotally connected by a king pin 18, the inner ends of the sections overlapping for the reception of the pin.

A broad turn-table bearing for the two sections is provided at 19 and a mechanism comprising a hydraulic cylinder 20 on frame section

16, a pump 21 connected therewith by a valve-controlled flexible conduit system 22, and a piston rod 23 attached to the end 17a of the frame section 17, controls the alignment or angular relation of the frame sections for steering purposes. 5

A driving power unit, such as an internal combustion engine 24, is mounted on the forward frame section 17 and delivers propelling power to each of four independent rolls or drums 25, through a transmission mechanism comprising a power take-off 26, transmission and reversing unit 27, a drive shaft 28, a longitudinal differential 28a, a propeller shaft 29 for the front rolls or drums, a cross differential 30, individual chain drives 31 and 32 for the front drums, a propeller 15 shaft 33 for the rear rolls or drums, universal joints 34 and 35 and splined slip joint 36 in the rear propeller shaft, a second cross differential 37, and individual chain drives 38 and 39 for the rear rolls. The terms "front" and "rear" are 20 used herein for convenience in description but the machine operates equally well and at the same speed in either direction of travel so that there is, in reality, no "front" or "rear" except as an arbitrary designation. 25

Each roll or drum 25 is journalled for rotation in an individual sub-frame 40 that is spring-carried and pivoted to the main frame, transversely to the axis of the drums. Each roll or drum is provided with a plurality of radially projecting lugs or "sheep feet" 41, an enlarged detail of one of which is shown in Figures 4 and 5.

Operation

In use, the improved tamper is self-propelled 35 and may be steered by an operator by the manipulation of three-way valves 42 and 43 to admit liquid delivered by the pump 21 to the cylinder 20, to move the piston rod 23, which, in turn, moves the frame section 17 about the king pin 40 18 which will steer the machine while travelling in either direction, the direction of travel being under control of the operator by reversible gearing of a conventional type. Other means for moving the frame sections about the king pin for 45 purposes of steering, may be provided, as for instance, a hand wheel with suitable gearing or a mechanical drive from the engine.

In the steering mechanism illustrated, the pump 21 is driven constantly from the engine, 50 and its output by-passes back in a closed cycle when both control valves are closed.

Since the individual rolls or drums are carried in individual pivotal frames, each drum is free to follow the contour of the surface over 55

which it travels independently of the others, and the individual chain drives for the drums assure their turning without skidding, so that the lugs or "feet" will do their tamping work efficiently.

5. No other piece of equipment goes over the fresh fill and a thoroughly good job of tamping is therefore effected.

In Figures 4 and 5, details are shown of a renewable foot that is well adapted for use with this improved tamper. A radial lug 44 is permanently fixed to the drum 25 and at its outer end the lug has an inwardly tapering hole or socket 45 to closely fit a similarly tapered shank 46 on a foot 47 that is preferably made of hard steel to 15 resist wear. The shank is drawn firmly into the lug by driving a wedge 48 through slots provided in the lug and the shank for the purpose. The small end of the wedge is split longitudinally, as at 49, so that each side thereof may be oppositely 20 bent similarly to a cotter pin, to hold the wedge in place in the shank. The foot may be replaced when worn, by driving out the wedge to release it and inserting a new foot in the lug. The foot is preferably provided with a square or a rectangular 25 working surface and the shank and/or the lug may be either square or circular in cross section. Obviously, any suitable form of lug or foot can be used on the improved tamper.

What I claim and desire to secure by Letters 30 Patent is:

1. An earth tamper comprising a main frame composed of two overlapping sections joined by a king pin for limited relative pivotal movement, a motor carried on one section, two rollers having lugs journaled on each section, in axial alignment with each other, and mechanism for transmitting driving power from the motor to each roller differentially and inversely according to the relative resistance to turning of each roller.

2. An earth tamper comprising a main frame composed of two overlapping sections joined by a king pin for limited relative pivotal movement, means on the frame for imparting such relative pivotal movement to the sections, a motor carried on one section, two rollers having lugs journaled on each section, in axial alignment with each other, and mechanism for transmitting driving power from the motor to each roller differentially and inversely according to the relative 10 resistance to turning of each roller.

3. An earth tamper comprising a main frame composed of two overlapping sections joined by a King pin for relative pivotal movement, a motor carried on one section, a pair of sub-frames 15 pivotally mounted on each of the sections on axes substantially parallel to the normal directions of travel of the tamper, a roller journaled for rotation on each of the sub-frames on an axis transverse to the pivotal axes of said sub-frames, and mechanism for transmitting driving power from the motor to each roller differentially and inversely according to the resistance to turning 20 offered by the respective rollers.

4. An earth tamper comprising a main frame 25 composed of two overlapping sections joined by a king pin for limited relative pivotal movement, a motor carried on one section, a sub-frame pivotally mounted on each frame section on an axis substantially parallel to the normal direction of 30 travel of the tamper, a roller journaled for rotation on each sub-frame on an axis transverse to that of the sub-frame, and mechanism for transmitting driving power from the motor differentially to each roller.

35

MATTHEW S. ROSS.
